UNITED STATES PATENT OFFICE.

GEORGE W. EDDY, OF NEW BRITAIN, CONNECTICUT.

DESIGN FOR TOY FULMINATE-EXPLoder.

Specification forming part of Design No. **11,394**, dated September 2, 1879; application filed August 12, 1879.
[Term of patent 14 years.]

To all whom it may concern:

Be it known that I, GEORGE W. EDDY, of New Britain, in the county of Hartford and State of Connecticut, have invented a new and original Design for a Toy Fulminate-Exploder, of which the following is a specification.

My invention relates to toys composed of two parts adapted to be brought together by concussion or a sudden jerk of a suspending-string, for exploding caps, fulminate-powder, and other explosive material.

The invention consists in a design for such a toy whereby it is caused to simulate the appearance of the head and face of a living creature, the two parts being made susceptible of operation in such manner as to resemble the motions of a mouth.

In the accompanying drawings, Figure 1 is a perspective view of a toy embodying my invention and resembling a human head and face. Fig. 2 is a similar view of such a toy representing the head and face of an animal. Fig. 3 is a similar view of such a toy resembling the head of a bird, and Fig. 4 is a similar view of such a toy resembling the head of a fish.

Similar letters of reference designate corresponding parts in all the figures.

Referring first to Fig. 1, A B designate two parts together, representing by their contour the head and face of a man, the sides of the two parts which serve to hold and explode the caps, fulminate-powder, or other explosive material being susceptible of being brought into and out of contact in such relation as to

represent a mouth and simulate the operation of a mouth. The part B has a shank, *b*, fitting in a slideway, *a*, in the part A, and is provided with a ring, *c*, for attachment to a cord, whereby the toy may be suspended. Fig. 2 shows a similar toy, adapted by its contour to represent the head and face of an animal. Fig. 3 shows a similar toy, made to represent the head and face of a bird; and Fig. 4 represents a similar toy, shaped to resemble the head and face of a fish.

By my invention I produce a toy for exploding caps, fulminate-powder, and other explosive substances, which, owing to the grotesque design, is calculated to afford great amusement to the possessor.

What I claim as my invention, and desire to secure by Letters Patent, is—

1. The design for a toy for exploding caps, fulminate-powder, or other explosive materials, consisting in the representation of the head and face of a living creature.

2. The design for a toy for exploding caps, fulminate-powder, or other explosive materials, consisting in the representation of the head and face of a living creature, the parts of the toy being adapted to represent a mouth and simulate the operation of a mouth.

3. The design for a toy for exploding caps, fulminate-powder, and other explosive materials, consisting in the representation of the head and face of a human being.

GEO. W. EDDY.
